LENS GRINDING AND POLISHING MACHINE

William A. Lockhart, Geneva, N. Y., assignor to
 Shuron Optical Company, Inc., Geneva, N. Y.,
 a corporation of New York

Application February 2, 1937, Serial No. 123,642

19 Claims. (Cl. 51--160)

This invention relates to improvements in a grinding and polishing machine for lenses or analogous articles.

The main object of this invention is to provide

5 a durably constructed, highly efficient apparatus for grinding and polishing the surfaces of lenses or analogous objects and particularly, curved surfaces such as found in bifocal and toric lenses having more or less complex curvatures.

10 In carrying out the above mentioned object, I have produced a grinding and polishing mechanism having several important and distinctive features which peculiarly adapt the mechanism for efficaciously producing exceptionally high grade work, that is, for producing a polished surface which is not only accurate in that it corresponds exactly to the surface of the grinding lap, but is also free from distortions and waves. This desirable result I accomplish, at least in part, as 15 follows:

First, by providing operating means whereby the grinding and polishing is effected by compounded rectilinear and circular motions imparted to the grinding and polishing couple by 20 which the path of traversing movement thereof is continually changing throughout the successive strokes and cycles of operation so that a given point on the surface of the movable member, whether it is the lens or the lap or both, very 25 seldom, if ever, travels twice in the same path.

Second, by producing a relatively high pressure between the lens and lap, and at the same time maintaining such pressure substantially constant throughout the cycles of operation irrespective of variations in the thickness of either 30 the lens or the lap or in both the lens and lap, and also by providing means whereby the lap spindle is prevented from axial vibration during the grinding and polishing action, particularly 35 when the radius of curvature of the lens surface is relatively short.

Third, by maintaining a film of abrasive or grinding material between the lens and lap at all times by periodically releasing the pressure 40 between lens and lap only sufficiently to permit said material to be worked therebetween and prevent a partial vacuum that otherwise would be formed between the lap and lens. However, I do not at any time entirely separate the lens and 45 lap while the machine is in operation as this would result in the formation of waves and distortions in the surface of the lens when operating under high pressure and impair or destroy the usefulness of the lens.

50 Fourth, by providing the machine with an ad-

justment for bringing the axis of the lens into alignment with the corresponding axis of the lap when a lens is remounted in the machine as for polishing.

In addition to the above, it is an object of this invention to provide the machine with a time control mechanism which may be selectively set to automatically govern the period of operation of the machine, depending upon the condition and degree of curvature of the surface to be 50 treated, the amount of abrasive material used, etc., whereby an operator may have charge of several operating machines at the same time.

Another object of the invention resides in providing an adjustable means for varying the degree 55 of movement of the motions of operation of the grinding and polishing couple.

A further object is to provide an operating mechanism for the grinding and polishing couple having both reciprocal and circular motions with 60 means for selectively changing the speed of operation of said motions independently of one another whereby the machine may be operated at a relatively high speed when grinding or polishing relatively weak lenses, that is, lenses up to 65 ten diopter, and to operate the machine at a slower rate of speed when grinding or polishing relatively strong lenses, that is, all lenses of ten diopter or more. Furthermore, the speed of operation may be controlled whereby the reciprocal movements for the cylinder and base curves may be controlled independently of each other when one of said curves is of relatively long radius, and the other curve is of relatively short 70 radius.

75 A still further object of the invention is to provide the machine with a compensator which, when the machine is used for grinding or polishing lenses or surfaces of complex curvatures, mechanically and automatically assists in reversing 80 the direction of movement of the movable elements of the couple at the end of each reciprocal movement.

Other objects and advantages pertaining to the 85 structure of the apparatus and to the form and relation of the parts thereof will more fully appear from the following description taken in connection with the accompanying drawings in which:

Figure 1 is a perspective view of an apparatus 90 embodying the various features of this invention.

Figure 2 is an enlarged detail transverse sectional view taken substantially in the plane of the line 2-2, Figure 1.

Figure 3 is a detail vertical sectional view 95

through a portion of the automatic time control mechanism taken substantially in the plane of the line 3—3, Figure 1.

Figure 4 is a longitudinal vertical sectional view taken substantially in the plane of the line 4—4, Figures 1 and 6.

Figure 5 is a horizontal sectional view taken on line 5—5, Figure 4.

Figure 6 is a transverse vertical sectional view taken on line 6—6, Figure 5 with the lower portion of the housing broken away.

Figure 7 is a detail horizontal sectional view taken on line 7—7, Figure 6.

Figure 8 is a detail vertical sectional view taken on line 8—8, Figure 6.

Figure 9 is a detail horizontal sectional view taken on line 9—9, Figure 6.

Figure 10 is a detail side elevation, partly in section, taken substantially in the plane of the line 10—10, Figure 6.

Figure 11 is a sectional view taken on line 11—11, Figure 4.

Figure 12 is a sectional view taken on line 12—12, Figure 6.

Figure 13 is a detail sectional view taken substantially on line 13—13, Figure 5.

Figure 14 is a vertical sectional view through the lens block and the supporting yoke therefor, together with the upper portion of the lap taken on line 14—14, Figure 5 and illustrating a plus or convex lens between the block and lap.

Figure 15 is a view similar to Figure 14 illustrating the lap and block with a minus or concave lens mounted in operative relation therewith.

Figure 16 is a detail horizontal sectional view taken on line 16—16, Figure 4.

Figure 17 is a diagrammatic view illustrating the lens holder during a movement thereof through the base stroke together with the action of the compensator thereupon.

Figure 18 is a diagrammatic view illustrating the path of the center of the lens during the movement thereof through the cycles of reciprocal movements.

Figure 19 is a similar view illustrating a portion of the path of the center of the lens produced by the combination of the reciprocal motions with the circular motion.

The apparatus as illustrated in the drawings comprises a main supporting frame or housing 1 having a cover 2 removably secured to the upper side thereof. The lower forward portion of the housing 1 is forwardly projected as at 3 and this projection is provided with a bottom 4 and side walls 5 which form a tray adapted to catch the waste abrasive. To the upper portion of the opposite or rear end of the housing 1 is secured a gear case 7 by means of screws 8 or the like, as shown in Figure 4. The gear case is provided with a normally closed bottom wall 9 to enable it to retain a quantity of oil for lubrication purposes, while the upper side of the case is closed by a cover 10 removably secured thereto. The inner side wall of gear case 7 is provided with bearing supports 12 and 12' which project outwardly therefrom through a recess 13 provided in the rear end wall of housing 1 into the interior of said housing.

In the upper portion of the gear case 7 are mounted a plurality of, in this instance, three horizontally disposed drive shafts 14, 15 and 16, which, as shown in Figures 4, 5 and 8 extend transversely through the case and are arranged

in parallel spaced relation to each other longitudinally of said case. These drive shafts may be journaled in any suitable manner in the side walls of gear case 7 and each shaft extends rearwardly beyond the rear side wall of the case and has operatively connected therewith one or more respective pulleys 17, 18 and 19. Each of the pulleys 17, 18 and 19 is connected by a respective belt 20 with a corresponding drive pulley 21, 22 and 23 secured to the outer end of a driven shaft 10 24 which is rotatably mounted, as shown in Figure 4, in a horizontal plane beneath the gear case 7 in a supporting bracket 25 secured to the rear end wall of the housing 1. Secured to the driven shaft 24 is a gear 26 which has meshing 15 engagement with a gear 26' secured to one end of a drive shaft 27 which is also journaled in the bracket 25 to extend substantially normal to the shaft 24. Mounted on the outer end of shaft 21 are pulleys 28 and 29, one of said pulleys 20 as 28, being secured to the shaft in any suitable manner to form a drive pulley, while the other one is an idle pulley rotatably mounted on said shaft.

Mounted in the gear case 7 are also a plurality 25 of, in this instance three, counter shafts 30, 31 and 32 which are journaled in the side walls of the case to extend in a horizontal plane beneath the drive shafts 14, 15 and 16 respectively, as shown in Figures 4, 5 and 8. The drive shafts 30 14, 15 and 16 are each operatively connected with a coupling or gear member 34 mounted upon each drive shaft within the gear case. Each of these coupling members has the ends thereof provided with a set of gear teeth 35 and 36 of different 35 pitch diameters and which are adapted to mesh with gear members 37 and 38 respectively which also differ in size one from the other and are fixedly secured to the corresponding counter shaft. As shown each set of gear teeth 35 and 40 gears 37 are of the same pitch diameter while the pitch diameter of gear teeth 36 is smaller than that of gears 38. It therefore follows that when gear teeth 35 mesh with a gear 37 the corresponding shafts will rotate at the same speed 45 and when teeth 36 mesh with a gear 38 the corresponding counter shaft will be rotated at a slower speed than that of the drive shaft.

The coupling members 34 are each slidably mounted upon their respective shafts and are 50 splined thereto so as to be rotated thereby. Each coupling member is moved axially along the shaft by a forked arm 39 adapted to ride in a peripheral groove 34' formed in each coupling 34. Each arm 39 extends upwardly above the corresponding 55 drive shaft to a position adjacent the inner face of the cover 10 and has secured thereto a control member or button 40 having a screw 40' which extends downwardly through an elongated slot 10' formed in said cover transversely thereof into screw threaded engagement with the corresponding arm 39 as shown in Figures 4 and 8. A washer 41 may, as shown, be inserted between each control button 40 and the cover 10 for closing the slot 10', and which co-acts with the button and screw for clamping the arm to the cover whereby the corresponding coupling 34 may be releasably secured in the adjusted position for selectively maintaining the gear members 35 and 36 in meshing engagement with the 70 corresponding gear members 37 and 38.

It will now be observed that each drive shaft 14, 15 and 16 and the corresponding counter shaft 30, 31 and 32 together with the gear connection therebetween constitute a variable speed power 75

transmission mechanism. Each of these mechanisms is utilized to produce one of the compounded rectilinear and circular motions imparted to the movable elements of the grinding and polishing couple in the following manner:

Lens holder operating means

Three substantially rectangular frame carriers 43, 44 and 45 are horizontally disposed within the housing 1, as shown in Figures 4, 5, 6 and 16, in cooperative relation with each other. 43 is a base carrier for producing reciprocal movement of the movable elements of the grinding couple along the base curve or longitudinally of the lens; 44 is a cylinder carrier for moving said elements along the cylinder curve or transversely of the lens; and 45 is a spindle carrier which supports a spindle 46 for actuating a lens holder and which is adapted to transmit the circular motion to said holder. The base carrier or frame 43 is reciprocally mounted upon a plurality of, in this instance four, studs 47, secured as shown in Figure 16, to the side walls of housing 1. The cylinder carrier frame 44 is mounted within the base frame 43 and is supported as shown in Figure 16, by said base frame for reciprocative movement relative thereto by four, studs 48 secured to the end portions of the frame 44 to extend outwardly therefrom at substantially right angles to the studs 47 and have the outer ends thereof slidably supported in suitable bearing members provided in the ends of base frame 43.

The base frame 43 is operatively connected with one of the counter shafts as 32 by means of a pitman rod 50 which is pivotally connected at one end to a side of frame 43 intermediate the ends thereof by a pin 51. The pitman rod extends in a substantially horizontal plane across the frame 43 and has the other end thereof journaled upon a drive pin 52 secured to or made integral with a drive block 53 which is slidably mounted in a diametrically disposed slot 54' provided in an enlarged head 54 secured to or made integral with a vertically disposed shaft 55. This shaft 55 is journaled in a bearing support 56 secured to the adjacent side wall of housing 1, as shown in Figure 6, which has the upper end thereof arranged in spaced relation to cover 2. Mounted upon shaft 55 adjacent the upper end of bearing support 56 is a gear member 57 which has meshing engagement with a similar gear member 58 secured to the inner end of counter shaft 32 and by which shaft 55 is rotated.

The hub 57' of gear 57, as shown in Figure 6, extends upwardly through an aperture provided in the cover 2 and has secured to the outer end thereof a flanged dial 59. Shaft 55, in this instance, is a tubular member and has journaled therein a spindle 60 which extends above the dial 59 and has secured to the upper end thereof a pointer 61 which is adapted to register in any one of a plurality of recesses 62 provided in the flange of said dial, as shown in Figures 1 and 6. The lower end of spindle 60 is provided with a pendant boss or pin 63 arranged eccentrically relative to the spindle 60 and which extends into an elongated slot 64 in the block 53 arranged transversely thereof substantially normal to recess 54' in head 54, as shown in Figure 12. The spindle 60 is also adapted to move vertically relative to shaft 55 and this vertical movement of the spindle is limited by means of a stop screw 65 secured in the hub 57' of gear 57 and which extends through the shaft 55 into a peripheral groove or recess 66 formed in the spindle, said recess being

of greater axial width than the diameter of the adjacent end of the screw.

It will now be observed that the degree of travel of pitman 50 and frame 43 may be controlled during the operation of the machine by lifting spindle 60 sufficiently to bring the pointer 61 out of registration with one of the dial recesses 62 and then rotating said spindle to bring the pointer into engagement with another one of said recesses and thereby effect movement of drive pin 52 toward or from the axis of shaft 55 by movement of the supporting block 53 relative to the head 54. It is to be understood that the width of recess 66 and the diameter of the inner end of screw 65 are so related that the spindle 60 will be prevented from being moved upwardly a sufficient distance to completely move the boss 63 out of the slot 64.

The cylinder carrier or frame 44 is operatively connected with the counter shaft 31 and for this purpose is provided with an extension 68 which projects from the rear end thereof over the adjacent end of frame 43; see Figure 4. The upper surface of extension 68 is provided with a transversely disposed slot 69, as shown in Figure 11, in which is mounted a bearing member 70 adapted to move longitudinally through said slot. In the bearing member 70 is journaled a driven pin 71 which is connected with the lower side of a drive block 72, mounted for reciprocated movement in a diametrically disposed recess 73 provided in a head 74 secured to or made integral with a vertically disposed shaft 75 which is journaled in the hereinbefore mentioned bearing support 12 connected with the gear case 7. The shaft 75 extends upwardly beyond the support 12 and has secured thereto a gear member 76 which is in meshing engagement with a similar gear 77 secured to the inner end of shaft 31, as shown in Figure 4, to be rotated thereby.

The gear 76 has the hub 76' thereof extended like the hub of gear 57 upwardly through an opening provided in cover 2 and has secured to the upper end thereof a flanged dial 77 adapted to rotate with said gear. Shaft 75 is a tubular member and has journaled therein a spindle 79 which extends above the dial 77 and has secured thereto a pointer 80 adapted to register in any one of a plurality of recesses 81 formed in the flange of said dial, as shown in Figures 1 and 4. The lower end of spindle 79 is provided with a pendant pin or boss 83 which is arranged eccentrically therewith, as shown in Figure 11. The boss 83 extends into an elongated slot 84 provided in the upper face of the drive block 72 and which extends substantially normal to slot 69. Spindle 79 is maintained against excessive vertical movement by means of a stop screw 85 secured in the hub 76' of gear 76 and the adjacent portion of shaft 75 as shown in Figure 4, and which extends into a peripheral groove or recess 86 provided in spindle 79. The relation of the inner end of the stop screw 85 and the width of the recess 86 are such that the pointer 80 may be lifted out of registration with a recess 81 by vertical movement of spindle 79 without completely disengaging the boss 83 with the drive head 72. One reason for providing means for varying the stroke of the base and cylinder frames is to enable the machine to efficaciously grind surfaces which vary from a substantially flat surface to curved surfaces having relatively short radii, the flat surfaces requiring the longer stroke.

The spindle carrier or frame 45 is operatively connected with the cylinder frame 44 to be recip-

located thereby and at the same is operatively connected with the counter shaft 30 mounted in gear case 9 to be actuated by said shaft with a circular motion in the following manner:

5 Two stub shafts 88 are journaled in vertical position, one at either end of frame 44, in axially spaced bearing members 89 secured to said frame. The lower end of each shaft 88 extends a short distance below the frame 44 and has secured thereto a gear 90 which is in meshing engagement with a similar gear 91. The gears 91 are secured to a horizontally disposed shaft 92 journaled in a support 93 secured to the underside of the frame 44, as shown in Figure 4. Secured 10 to the shaft 92, as shown in Figures 4 and 9, is a spur gear 95 which is in meshing engagement with a spur gear 96 secured to one end of a stub shaft 97 which is journaled in the support 93 in parallel relation with shaft 92; see Figure 9. The 15 other end of shaft 97 is connected by a universal joint 98 with one end of a shaft 99 which has the other end thereof connected by a similar universal joint 98 with a stub shaft 100 journaled in the rear end wall of housing 1 in a horizontal 20 plane beneath the gear case 9 and in a vertical plane extending intermediate the counter shafts 30 and 31. To the shaft 100 is secured a sprocket wheel 101 which is connected by a sprocket chain 102 with a second sprocket wheel 103 secured to 25 the inner end of counter shaft 30, as shown in Figure 8.

Shaft 99 is a sectional member, one section of which, as 99', has a tubular end portion which slidably receives an end portion of the second 30 section as 99'' therein, said sections being secured together to cause the same to rotate in unison by a pin and slot connection 104. It will be observed that the purpose of the shaft 99 being formed in section and the connection thereof 35 with shafts 97 and 100 by universal joints is to permit the free reciprocative movements of shaft 97 with frames 43 and 44.

The upper ends of the shafts 88 terminate substantially flush with the upper face of the 40 adjacent portion of the frame 44 and each shaft 88 is provided with an upwardly extending boss or pin 105 arranged eccentrically therewith. Mounted on each pin 105 is a sleeve 106 which, in turn, is mounted in a bearing member 107 45 mounted in the lower side of the spindle frame 45; see Figures 4 and 6. The bearings 107 are spaced apart a distance substantially equal to the distance between the axes of shafts 88 so that during rotation of said shafts, a circular 50 motion corresponding to the degree pins 105 are offset from the axes of shafts 88 will be transmitted to the spindle frame through the medium of pins 105 and bearings 107 relative to the cylinder frame 44.

55 The spindle frame 45 is provided with a pair of upwardly projecting arms 109 and 110 arranged one adjacent the rear and forward ends thereof respectively. The upper ends of the arms 109 and 110 are each provided with a bearing member 111 which rotatably supports the hereinbefore mentioned spindle 46. The spindle 46 is fixedly secured to one of the bearings 111 by a nut 46'; see Figure 5, whereby the spindle will reciprocate in unison with said bearing 60 and with the frame 45. The forward arm 110 projects forwardly from the frame 45 in close aligned relation with an opening 112 provided in the forward end of housing 1. This opening is somewhat larger in diameter than the upper 65 end portion of arm 110 to permit free lateral 70 movement of said arm therein.

75 movement of said arm therein. A flexible diaphragm 113 composed of leather, rubber or the like, is secured to the housing 1 to extend across the opening 112 adjacent the outer face of the upper end of arm 110 for tightly closing said opening to prevent dust or abrasive entering the housing or oil splashing out. The diaphragm has a central opening 113' through which the outer end portion of the spindle 46 extends, said opening being of substantially the same diameter as the spindle so that the diaphragm will closely engage said spindle. To the outer end of spindle 46 is secured a U-shaped support or yoke 114 which has the arms 114' thereof extending forwardly from the spindle in substantially the 15 horizontal plane of the spindle.

Lens holder

To the outer end of each arm 114' is secured a pivotal screw 115; see Figure 2. These pivotal screws extend inwardly from the arms 114' in substantially coaxial alignment with each other and rotatably engage a respective arm 116 of a lens holder 117 which also includes a cross bar 118 and a lens supporting block 119. Each of these arms 116 extends upwardly from the corresponding screw 115 and is provided with a recess 116' which extends longitudinally thereof from near the upper end of the arm toward the pivotal screw for adjustably receiving therein the corresponding end of cross bar 118. Each end portion of the cross bar 118 is provided with a key member 118' positioned in the slot 116', see Figure 2, to maintain said bar and member against relative rotation. A threaded cylindrical portion extends from the key 118' and a flanged nut 120 is screw threaded thereon which co-acts with a corresponding shoulder 118'' adjacent the key member for adjustably clamping the arm 116 to the cross bar. Each arm 116 has one vertical side thereof provided with spaced index lines 121 adapted to align with a guide line 122 formed on the shoulder 118'' and adjacent portion of the cross bar, as shown in Figure 2, whereby the cross bar may be readily arranged in predetermined spaced relation to the pivotal screws 115 for maintaining differently formed lenses in predetermined relation with the axis of pivotal screws 115 and of spindle 46 for a purpose which will hereinafter more fully appear.

The lens supporting block 119, as shown, is circular in plan view and is provided with a diametrically disposed rib 119'. The cross bar 118 is provided with a pair of clamping plates 124 and 125 which are L-shaped in longitudinal cross section, as shown in Figure 4. One of the clamping plates as 124 is fixedly secured by any suitable means to the rear side of the cross bar 118 substantially midway between the ends thereof. The other clamping plate 125 is removably secured to the cross bar by a thumb screw 126. The ends of the clamping plates opposite the transversely disposed flange thereof which as shown engage the upper edge of the cross bar 118, extend a short distance below the cross bar for receiving the lens block rib 119' therebetween. These lower portions of the plates preferably have the inner adjacent surfaces thereof serrated for gripping the longitudinal sides of the rib so that the lens block may thereby be releasably secured to the cross bar 118. The degree of rocking movement of arms 114 and, therefore, cross bar 118, about screws 115 is limited by a stop pin 127 secured to the lower end of each arm and which extends outwardly 75

Pressure means

The lower end of the spindle 129 extends below the bottom wall 4 into the lower portion of the base projection 3 and contacts with one end of an arm 145 which extends rearwardly from the spindle. The other end of arm 145 is clamped or otherwise secured to the inner end of a sleeve 146, as shown in Figures 4 and 6. Sleeve 146 extends transversely of the housing 1 and is journaled in one side wall thereof some distance at the rear of the spindle 129. A shaft 147 is journaled in the sleeve 146 and has one end thereof rotatably mounted in the opposite side wall of housing 1 to that in which sleeve 146 is journaled, as shown in Figure 6. The sleeve 146 extends from a position substantially midway between the side walls of the housing to a position a relatively short distance beyond one of said walls. Sleeve 146 is maintained against outward axial movement by a flange 146' connected therewith and which engages the inner side of the wall of the housing in which the sleeve is journaled. The sleeve 146 is maintained against inward axial movement by a spacing sleeve 148 and a collar 149 mounted on shaft 147 intermediate the inner end of sleeve 146 and the opposite side wall of housing 1, as shown in Figure 6. This collar 149 is secured to the shaft 147 to rotate therewith and has one end of a relatively heavy, stiff spring 150 connected therewith. This spring is coiled about the sleeve 148 and has the other end thereof extended forwardly from the sleeve into engagement with arm 145 a short distance from the outer end thereof as shown in Figure 4 for yieldingly urging the arm upwardly when shaft 147 is rotated.

Rotation of shaft 147 is produced by a lever 152 secured at one end to the outer end of the shaft. This lever extends, as shown in Figure 10, forwardly from shaft 147 adjacent the outer face of housing 1 to the forward end thereof which is bent downwardly to form a hand grip 153. The underside of said lever is provided with a recess 152' which extends inwardly from the grip 153 to a position intermediate the ends of the arm where said arm is offset as at 154, Figure 5, to form a recess 154' at the inner side of the lever in alignment with the recess 152'. In the recess 152' is positioned a rod detent 155 which is mounted for longitudinal reciprocative movement, as shown in Figure 10, with one end thereof positioned in an aperture provided in the hand grip 153, while the other end of the rod detent extends into the recess 154'. Upon the rod 155 is secured a finger piece or trigger 156 which is normally positioned a short distance inwardly from the hand grip 153 and a spring 157 mounted on the rod between the finger piece and hand grip normally urges the rod inwardly, said inward movement of rod being limited by the engagement of the finger piece 156 with one of a pair of guide pins 158 which extend transversely of the recess 152' for maintaining the rod 155 in said recess.

A ratchet lever 160 is rotatably mounted intermediate its ends upon shaft 147 intermediate the lever 152 and the outer end of sleeve 146, as shown in Figure 6. One arm as 160' of the ratchet lever extends forwardly from the shaft 147 into the recess 154' and has the outer end thereof arranged concentrically with the shaft 147 and provided with serrations or ratchet teeth 161 adapted to be engaged by the rod detent 155. The other arm 160'' of the lever 160 extends rearwardly from the shaft 147 into engagement with

therefrom between a pair of spaced limiting pins or shoulders 127' secured to the outer ends of arms 114' of the yoke 114, as shown in Figures 2 and 4 whereby the lens holder is maintained in a more or less vertical position when inoperative.

Lap supporting means

A grinding lap 128 adapted to cooperate with the lens block 119 for grinding surfaces is removably mounted upon the upper end of a supporting spindle 129 which extends vertically through a bearing member 130 mounted in a bearing support 131 secured to the bottom 4 of the housing projection 3. The bearing support 131, in this instance, is a cylindrical member which extends upwardly some distance beyond the bottom wall 4 and has the lower end thereof extending through a suitable aperture provided in said wall. The bearing member 130 comprises a cylindrical ball race 132 composed of tempered steel or the like, of greater interior diameter than the diameter of spindle 129. This ball race extends axially through the bearing support 131 and is secured therein by nuts 133 screw threaded one in either end of the bearing support. Within the ball race 132 is rotatably mounted a cylindrical retaining member 134. This ball retaining member is adapted to easily fit between the spindle 129 and the ball race 132 and is provided with a multiplicity of apertures, each of which receives therein a respective bearing ball 135 adapted to have a free rolling engagement with the inner wall of the ball race and with the spindle 129. It is, therefore, seen that the spindle 129 is supported for a considerable portion of the axial length thereof by the bearing member 130, whereby said spindle may move vertically with a minimum amount of friction. This feature is very essential in order that the spindle may be easily held steady against axial vibration or chattering during the grinding operation.

In order that laps of different sizes and formations may be readily secured to the spindle 129, the upper end of the spindle is provided with a head 137 which is adapted to be removably connected therewith. Adjacent opposite sides of the head 137 are positioned clamping plates 138 and 139 which are connected with the head for movement toward and from each other by a clamping screw 140 extending through aligned openings provided in the plates and head and a finger nut 141 screw threaded on the clamping screw, as shown in Figure 4. The upper end portions of the clamping plates 138 and 139 extend a short distance above the head 137 and then inwardly over the head into frictional engagement with the lap 128. The head 137 is maintained against rotation relative to spindle 129 by a pin 143 secured in the upper end of the spindle and which extends outwardly from one side thereof into a slot 137' formed in the lower portion of the support 137.

The spindle 129 is provided with a peripheral shoulder 129' arranged a short distance below the head 137 and an inverted cup-shaped cap 144 is mounted on the upper end of the spindle in engagement with the shoulder 129'. This cap extends downwardly over the bearing support 131 and contacts with an outwardly extending marginal flange 131' formed on the upper end of said support, as shown in Figure 2, for preventing dust and grinding materials from passing to the interior thereof and to the bearing member 130.

the lower end of a vertically disposed push rod 162. This rod extends upwardly through the adjacent side wall of housing 1 which extends outwardly over the lower portion of the housing, as shown in Figures 6 and 10 and through an upwardly extending guide boss 163 secured to or made integral with said wall at the inner side thereof. The upper end of the push rod has secured thereto a head 164 which is adapted to be engaged by a cam 165 secured to a shaft 166 which extends transversely of the housing 1 and has the ends thereof journaled in opposite side walls of said housing. The cam 165 is adapted to intermittently force the push rod 162 downwardly during rotation of the shaft 166 for effecting rocking movement of the ratchet lever 160 and the lever 152 connected therewith by the rod detent 155.

Secured to the outer end of the sleeve 146 intermediate the lever 160 and the adjacent side wall of the housing 1, is a sector-like dial member 168 which extends forwardly from the sleeve 146 and has the outer end 169 thereof arranged in a vertical plane concentric with the sleeve, see Figure 10. The outer peripheral face of end 169 is provided with indicia in the form of index lines 170 spaced to represent pounds pressure or fractions thereof exerted by spring 150 through arm 145 upon spindle 129. These lines 170 are arranged to align with a lateral projection 171 provided on the inner face of the lever 152 adjacent the end 169 as shown in Figure 5.

The lower portion of the outer end of the dial member 168 is provided with a laterally projecting lug 172 which extends beneath the lever 152 for limiting the swinging movement of the lever downwardly relative to said member.

It will now be observed that the vertical movement of spindle 129 for bringing the lap 128 into and out of cooperative relation with a piece of work, as lens L, Figures 14 and 15, secured to the lens block 118, may be controlled by the manipulation of the lever 152, in the following manner. When the lever 152 and arm 145 are in their lowermost position, as shown in Figures 4 and 10, the upward movement of lever 152 will effect rotation of shaft 147 in a corresponding direction. This rotation of shaft 147 will be transmitted by collar 149 and spring 150 to arm 145. The upward swinging movement of arm 145 thus produced, prior to the engagement of the lap 128 with the work L, will effect a corresponding rotation of sleeve 146 and also of the dial 168. Inasmuch as the resistance to the upward movement of the arm 145 produced by the spindle 129 is insufficient to tension spring 150, the dial 168 and lever 152, together with arm 145 will rotate in unison until the lap 128 engages the work L which prevents further upward movement of spindle 129.

The continued upward movement of lever 152 after the spindle 129 is thus held by the work will place spring 150 under tension due to the rotation of shaft 147 and collar 149 produced thereby, and to the arm 145 being maintained against further upward swinging movement by the spindle 129. It will now be obvious that during the movement of the lap into operative engagement with the work there will be no appreciable tensioning of spring 150 produced. However, as soon as the lap engages the work, continued upward movement of lever 152 will tension spring 150 and the degree of said tension may be readily controlled by the amount of this upward rotation of lever 152 which is easily determined by the registration of the projection or

pointer 171 on the lever with indicia 170 on the dial 168. During the upward rotation of lever 152 the rod detent 155 is of course maintained out of contact with the ratchet teeth 161 by the operator moving the rod outwardly against the action of spring 157. Furthermore, during this upward rotation of lever 152, the ratchet lever 160 will remain stationary with the arm 160' thereof maintained in contact with the push rod 162 due to the preponderance of weight being in arm 160' which also maintains the head 164 of the push rod in contact with cam 165. When the lap 128 is brought into engagement with the work L under the desired pressure produced by the tensioning of spring 150, this pressure may be maintained by the engagement of the rod detent with the ratchet teeth 161 of the ratchet lever 160 due to the cam 165 contacting push rod 162.

It will also be understood that when the lap is thus maintained in pressure engagement with the work, rotation of cam 165 from the position shown in Figure 10 will intermittently permit the upward movement of push rod 162 which releases the arm 160' of the ratchet lever 160 and permits the other arm 160' thereof together with the lever 152 connected therewith to swing downwardly a corresponding distance. This downward movement of lever 152 will obviously rotate shaft 147 in a direction to decrease the tension of spring 150 and thereby reduce the pressure between the grinding lap 128 and the lens L. This reduction in pressure is sufficient to permit the grinding abrasive which is forced from between the grinding lap and lens by the high pressure produced therebetween to again enter between the contacting surfaces of the lap and lens as the lens is moved with the rectilinear and circular motions relative to the lap. It is to be understood, however, that the action of cam 165 upon lever 152 is insufficient to permit the lap to move out of contact with the lens as is the case in some lens grinding machine structures, and thereby prevent the forming of waves or the distortion of the lens surface which would result when using the high pressure obtained in this mechanism if the lap and lens were caused to intermittently separate during the grinding operation.

As hereinbefore stated, the lens holder 117 is maintained in a more or less inclined vertical position when the lap 128 is in the lowermost inoperative position by the co-action of the stop pins 127 and 127', as illustrated in Figure 4. As the lap is moved upwardly toward the lens holder, the engagement of the lap with the lens causes the holder to swing about the screws 115 as an axis and thereby automatically brings the surface of the lens into cooperative relation with that portion of the surface of the lap engaged thereby whether a flat, concave or convex lens is mounted on the lens holder.

In as much as spring 150 is a relatively strong member, the lens L will be maintained in engagement with the grinding lap under a relatively high pressure and thus obtain maximum speed of operation. It follows, therefore, that the resistance to the travel of the lens over the surface of the lap will be proportionally greater than when using a lesser degree of pressure as in the conventionally constructed grinding machines of this class. This is particularly the case when grinding or polishing a curved surface having short radii whether such surface is convex or concave due to the necessity of forcing the lens along the sharply upwardly inclined portions

thereof during each forward and backward stroke of the lens holder as will be apparent by referring to Figures 14 and 15.

In the lens holder 117 hereinbefore described, it will be noted that said holder rocks about the axis of the spindle 46 as the lens is moved along the longitudinal or base axis of the lap. It will also be noted that inasmuch as the cross bar 118 of the lens holder is adjustable longitudinally of the arms 116, the lens may be positioned with the surface thereof to be ground either above or below the axis of rotation of the spindle, that is, at the same side of said axis as the bar 118 or at the opposite side thereof depending upon whether a convex or concave lens is to be ground. This arrangement of the lens and work holder provides for the lens to be moved by a minimum amount of power over the upwardly inclined portions of the lap surface and without producing excessive lateral thrusts of the lens upon such surfaces and the resultant excessive wear thereto which would alter the contour of the lap and result in a defective lens. The operation of the lens holder to accomplish this result is as follows:

Consider first that a plus or convex lens, as illustrated in Figures 2 and 4, is to be ground. The lens L is positioned, as shown, with the surface thereof to be ground above the axis of rotation of spindle 46 and of the pivotal screws 115 by clamping the cross bar 118 to the arms 116 with the upper or outer positioned index line 121 in alignment with the guide line 122 on the cross bar.

It will now be apparent, by referring to Figure 14, that inasmuch as the longitudinal thrust of the spindle 46 upon the lens holder is applied at the pivotal screws 115 below the connection of the lens both with the lens holder bar 118 and with the lap 128, the frictional resistance to the movement of the lens over the lap will tend to rotate the holder in the opposite direction to that of the movement of the spindle 46. The forward edge of the lens will therefore, be rocked upwardly thereby and caused to move along the upwardly inclined edge portion of the lap surface coincident therewith and without producing excessive friction between the lap and lens. If, on the other hand, a minus or concave lens is to be ground, the cross bar 118 of the lens holder is secured to the lower portion of the arms 116, that is, with the lower index line 121 in alignment with the guide line 122. When so positioned, the lens surface to be ground will be positioned below the axis of the screws 115 and of the spindle 46 and at the opposite side of the spindle axis to that of bar 118, as shown in Figure 15. In this arrangement of the parts, the thrust of the spindle 46 during the axial movement thereof upon the lens holder will be applied thereto above the surface of the lens engaging the lap 128, that is, at the same side of said surface as the connection of the lens with the lens holder bar 118.

It, therefore, follows that the force produced by the lateral thrust of the lens upon the upwardly inclined central portion of said lap will be applied to the lens holder at the opposite side of the axis of spindle 46 to that of the lap engaging surface of the lens. This will tend to rock the lens holder in a direction opposite to the direction of movement of the spindle 46 and thereby tend to rock the forward edge of the lens upwardly so that the lens will move over said surface of the lap in substantially coinci-

dental contact therewith and therefore with a minimum amount of lateral thrust thereupon.

When a lens with a substantially flat surface is to be ground, such surface is maintained substantially in the plane of the axis of rotation of spindle 46 by clamping the cross bar 118 to the side arms 116 with the central index line 121 in alignment with the guide line 122. When the parts of the lens holder are in this position, the line of thrust of the spindle 46 during the axial movement thereof upon the lens holder is substantially coincident to the lines of thrust of the lens upon the grinding lap so that the tendency of the lens holder to be rotated about the axis of the screws 115 is reduced to a minimum and the surface of the lens will be maintained in substantially coincidental contact with the curved grinding surface of the lap.

The term "coincidental contact" is used in the specification and claims to designate that relation between the lens and lap whereby all portions of the surface of the lens being ground will engage insofar as possible the grinding surface of the lap and with a substantially uniform pressure throughout the area thereof in counter distinction to any inequality in the engagement of such surfaces that would occur if they were caused to assume a more or less angular relation therebetween.

The hereinbefore mentioned shaft 166 for operating cam 165 is driven by the drive shaft 16 mounted in the gear case 1 through the medium of a worm gear 173 secured to the inner end of said drive shaft which is extended beyond the bearing support 12' and a gear 174 secured to shaft 166 as shown in Figures 4 and 5.

As illustrated in Figures 5 and 8, the drive shaft 14 for producing the rotary movement of spindle frame 45 is provided with means for automatically reversing the direction of rotation thereof at predetermined intervals for reversing the direction of rotation of the spindle frame. This control mechanism for shaft 14 comprises providing said shaft with a pair of driven pulleys 17 which are rotatably mounted thereon, said pulleys being 45 rotated in reverse directions by crossing one of the belts 20 therefor. These pulleys are arranged in slightly axially spaced relation and are selectively connected with the shaft 14 to produce rotation of the shaft by a clutch mechanism. This clutch mechanism comprises, in this instance, a clutch control rod 176 mounted for longitudinal reciprocal movement in the interior of shaft 14 which, as shown in Figures 5 and 8, is a tubular member. The outer end of the rod 176 is provided with a 55 clutch pin 177 which extends outwardly radially therefrom through an elongated slot 14' provided in the adjacent portion of shaft 14 at one side thereof into the path of a pair of clutch pins 178, each of which is secured to a respective driven 60 pulley 17. The pins 178 are adapted to project from the respective pulley inwardly toward each other and have the inner ends thereof spaced from each other a distance to readily receive the clutch pin 177 therebetween so that when said 65 latter pin is positioned in a plane intermediate the pins 178 the pulleys 17 may freely rotate on shaft 14 without transmitting motion to said shaft.

The control rod 176 is moved longitudinally relative to the shaft 14 to bring the pin 177 into 70 and out of cooperative relation with the pins 178 by means of a cam 180 secured to the hereinbefore mentioned cam shaft 166. As shown in Figures 5, 6 and 8, a cam arm 181 is pivotally connected with the housing 1 above the shaft 166 by a pin 182 and 75

a link 183. The link 183 is pivotally connected at one end by a pin 184 to the arm 181 and rotatably connected at the other end to the inner end of rod 176 by a screw and slot connection 185 whereby 5 said rod may rotate with the shaft 14 relative to the link 183. The cam arm 181 has the lower end portion thereof provided with an aperture 186 which receives the shaft 166 and cam 180 therein. The opposite sides of the opening 186 are curved 10 inwardly as illustrated in Figure 8 to form a pair of diametrically opposed cam surfaces 187 spaced apart a distance substantially equal to the longer diameter of the cam 180 and which are adapted to be alternately engaged by said cam during the 15 rotation thereof for oscillating the arm 181 to effect axial movement of the control rod 176. A spring detent 188 connected with the housing 1 by a stud 189 and support block 190, as shown in Figures 5, 6 and 8, is adapted to frictionally engage 20 a V-shaped tooth 191 formed on the lower end of the arm 181 for releasably maintaining said arm and control rod 176 in their extreme positions of movement as produced by cam 180. It will now be readily understood that the operation of the 25 mechanism thus far described is as follows:

Inasmuch as the pulleys 19 and 23, as shown in Figures 4 and 5 for driving the power transmission mechanism for operating the base frame 43 are of different relative diameters than the pulleys 22 30 and 18 for operating the power transmission mechanism which actuates the cylinder frame 44, these frames will be operated at different speeds. For convenience let it be assumed that the speed of operation of the drive shaft 16 is one hundred 35 forty R. P. M. so that the base frame 43 actuated thereby will operate at two hundred eighty strokes per minute when the teeth 35 of the couple 34 on shaft 16 are in engagement with the gear 37 associated therewith. Let it also be assumed that the 40 speed of operation of the drive shaft 15 is one hundred thirty R. P. M. so that the cylinder frame 44 will be operated at two hundred sixty strokes per minute when the teeth 35 of the couple 34 mounted on the shaft 15 are in engagement with the 45 gear 37 associated therewith.

In addition to the above, it will be observed by referring to Figures 11 and 12 that the maximum degree of throw of the drive block 53 for the base frame is greater than the throw of the drive block 50 52 for the cylinder frame so that the rectilinear movement of the base frame 43 and, therefore, the movement of the lens longitudinally of the lap 128 will be greater than the rectilinear movement of the cylinder frame 44 and, therefore, of the movement 55 of the lens transversely of said lap.

This ratio of the longitudinal movement or throw to that of the transverse motion or throw of the base and cylinder frames in the structure illustrated is as 2½ to 1. By referring to Figures 60 4 and 5, it will be noted that the drive pulleys 21 and the driven pulleys 17 which operate the power transmission mechanism connected with the spindle frame 45 are of substantially the same diameter so that the speed of operation of the drive 65 shaft 14 is intermediate that of the speed of rotation of the shafts 15 and 16 or approximately one hundred thirty five R. P. M. It will thus be seen that when the teeth 35 of the couple 34 mounted on shaft 14 are in engagement with the 70 gear 37, the rotary movement of the frame 45 will equal that of shaft 14.

Assuming now that a lens L is secured to the lens block 119 and that the lap 128 has been moved into pressure engagement with the lens, 75 that each coupling element 34 has been moved by

the manipulation of the control buttons 40 to bring the teeth 34 thereof into engagement with respective gears 37 and that the drive blocks 53 and 72 for the base and cylinder frames have been set for maximum throw through the medium of 5 respective pointers 61 and 80.

Now as the drive shaft 21 is rotated by any suitable means as by a belt 193 mounted on drive pulley 28 and connected with any suitable source of power, it is obvious that the spindle 46 and lens L connected therewith will have a curvilinear movement across the grinding surface of the lap 128 compounded of two crank-produced rectilinear movements at right angles to each other and one circular movement.

Inasmuch as the stroke of the base frame 43 is substantially two and one-half times the stroke of the cylinder frame 44, if the base frame be operated at two hundred eighty strokes per minute and the cylinder frame correspondingly operated at two hundred sixty strokes per minute, the general path of movement of the lens over the face of the grinding lap produced by the two rectilinear movements only would be substantially as represented in Figure 18, while the actual 25 path of the lens over the surface of the lap produced by the combined actions of the base and cylinder frames with the spindle frame 45 will be substantially as indicated in Figure 19.

In Figure 18, the paths of movement have for 30 convenience been illustrated as straight lines. This is not strictly true, because the two rectilinear movements are produced by cranks rotating at different speeds, so that the resultant movement would not be exactly rectilinear, but, 35 it is quite close thereto, and on the assumptions made in the foregoing specific example the termini of the various strokes would be as illustrated in Figure 18.

To explain more explicitly, by referring to Figures 18 and 19, lines A—B, C—D represent the stroke of the base frame 43 and lines A—C, B—D represent the stroke of the cylinder frame 44. Now by referring to Figure 18 and assuming that the lens is moved over the lap, by the combined 40 action of the base and cylinder frames only and assuming that the starting position of the center of the lens surface to be ground is at a, then lines a—b, b—c, c—d, d—e, etc., will represent the general path of movement of the lens. In other words, the lens will move diagonally across 45 the lap until the center of the lens surface reaches position b on line B—D at which time the base frame 43 will have reached the end of its first stroke.

Inasmuch as the cylinder frame 44 travels slower than the base frame 43, it follows that as the base frame reaches the end of its first stroke, the cylinder frame will not have quite completed 50 its first stroke with the result that as the cylinder frame begins its second stroke, the continued movement of the cylinder frame to complete its first stroke will move the lens along the line b—c to the position c on line C—D. Then, as the cylinder frame begins its second stroke, the lens 55 will be moved along the line c—d to the position d on line A—C. As the lens reaches the position d, the base frame will have completed its second stroke, and as the base frame begins its third stroke, the lens will be moved along the line d—e 60 to the position e as the cylinder frame reaches the end of its second stroke. As the cylinder frame begins its third stroke, the lens will be moved along the line e—f, etc., during 65 the succeeding strokes of the base and cylinder frame.

inder frames. It will thus be observed that as the machine continues to operate, the general line of travel of the lens diagonally of the lap as from A to D will gradually decrease in length while the lines of the general direction of travel of the lens transversely of the lap from B to C will gradually increase in length until the lens reaches the position a' when the general direction of the lens will be from a' to b' to c' to d', etc.

It will thus be noted that while the lines a—b, b—c, c—d, etc., of the general path of movement of the lens over the lap are substantially parallel with corresponding lines a'—b', b'—c', c'—d', etc., none of these latter lines coincide with the former lines so that the lens will be driven back and forth across the face of the lap a multiplicity of times if actuated by the base and cylinder frames only, before the lens will travel twice in the same path. If now the rotary action of the spindle frame upon the lens is added to that of the base frame 43 and cylinder frame 44, it will be understood that while the general direction of the lens over the face of the lap is substantially the same as illustrated in Figure 18, the actual line of travel of the lens will be of a more circular or elliptical nature as illustrated in Figure 19 where the path of the lens is from x to y to z, etc. The lines of travel of the lens are further deviated one from another by fact of the belt drives between drive shaft 24 and driven shafts 14, 15 and 16 and the well known phenomena known as belt creep, whereby the driven pulley always rotates at a slightly slower peripheral speed than the drive pulley. Also when the circular motion of the spindle frame 45 is reversed by action of the clutch mechanism on pulleys 17 the line of travel of the lens is still further altered with the result that the operation of the lens may continue almost indefinitely before the lens will travel twice in the same path.

If other ratio values are desired from that taken in the illustration to distribute the grinding action of the lens upon the lap, this may readily be obtained during the operation of the machine by shifting any one or combination of the coupling elements 34 to bring the gear teeth 36 thereof in meshing engagement with corresponding gears 38, by altering the length of the throw of either the drive blocks 53 or 12 for the base and cylinder frames or both of these throws or by any combination of the throws and of the coupling elements. Furthermore, additional ratio values of operation may be quickly and easily obtained by rearranging the drive and driven pulleys 21, 22, 23, 17, 18 and 19 for the power transmission mechanisms in the gear case 7, said pulleys being made interchangeable for this purpose.

It will thus be seen that I have provided a machine having a drive mechanism for the lens which, when coupled with the relatively high pressure obtained between the lens and the grinding lap, will not only be very rapid in operation, but will also produce a polished surface which is free from distortion and is scientifically accurate.

Compensating device

In order to further enhance the efficiency of my surface grinding apparatus, particularly when grinding curved surfaces having relatively short radii, I have provided a compensating device which co-acts with the lens holder for maintaining a uniform pressure between the lens and lap by mechanically reversing the direction of move-

ment of the lens relative to the grinding lap at the end of each base or longitudinal stroke.

This compensating mechanism, as shown more clearly in Figures 4, 5 and 13, comprises a pair of contact arms or elements 195 arranged one at either side of a roll 196 secured to the spindle 46 intermediate the bearings 111. Each contact arm 195, as shown more particularly in Figure 13, comprises a plate 197 composed preferably of spring metal which has one end thereof rotatably mounted upon a spindle 198 mounted in a bracket 199. The ends of the plates 197 mounted on the spindle are each positioned between a pair of roller bearings 200 so that the plates are supported to freely rotate about the axis of the spindle 198. These plates 197 extend outwardly from the spindle a sufficient distance to remain in contact with the roller 196 during the reciprocal and rotary movement thereof produced by the action of the base, cylinder and spindle frames. The spring plates 197 are preferably reenforced by plates 201 positioned adjacent the outer sides thereof and secured thereto by a clamping bolt 202 which is positioned intermediate the roller 196 and spindle 198. The clamping bolt 202 is secured to the plates 197 and 201 by nuts 203 screw threaded on the bolt and positioned one at either side of each pair of plates whereby the outer ends of said plates may be adjusted toward and from each other by screw threading the nuts 203 upon the bolt 202 to properly position the outer ends of the plates relative to the roller 196 and then to secure said plates in the adjusted position.

The bracket 199 is mounted upon the housing 1 at one side of the spindle 46 by means of a square headed, shouldered stud 205 secured to the side wall of the housing and which has the head thereof positioned in a T-slot 199' provided in the outer vertical side of the bracket. The bracket 199 is moved vertically relative to the stud 205 by means of a screw member 206 journaled in the upper portion of the housing 1 as shown in Figure 13 and which has the lower end thereof screw threaded in the bracket 199. The upper end of the screw member 206 extends above the cover 2 and has secured thereto a lever 207 provided with a knob 208 by which the lever may be manually swung for rotating the screw 206.

The outer or free ends of the contact arms 195 are normally maintained by the bolt 202 spaced apart a distance slightly greater than the diameter of the roll 196 and the vertical movement of the bracket 199 produced by the screw 206 is for bringing one or the other of these arms into frictional engagement with the periphery of the roller 196 so that as the spindle 46 is moved laterally during the grinding operation, the roller 196 will move along the contact arm engaged therewith with a rolling motion.

The operation of the compensating mechanism will now be understood by referring to Figure 17 wherein the lap 128 is constructed for grinding a convex surface and the spindle 46 is indicated by full lines substantially midway between the extreme lateral positions assumed thereby during the grinding operation and in a plane substantially midway between the ends of the lap 128. When the spindle 46 and lap 128 are thus related to each other, the center of the lens will contact with the lap midway between the longitudinal axis thereof, as illustrated by the arrow M. Now considering that the spindle 46 is being moved toward the left hand side of the lap to

the position illustrated by broken lines, it will be observed that the roller 196 contacting with the upper disposed contact arm 195 will tend to roll in a clockwise direction so as to produce a rotary movement of the spindle 46 in the same direction. This rotation of the spindle 46 in a clockwise direction will produce a corresponding rotation of the lens holder 117 in the same direction so that as the lens moves from the lower central portion of the lap along the upwardly curved portion thereof the rocking action of the work holder as hereinbefore described will be assisted by the rotation of the spindle for reducing the thrust of the lens against the curved surface of the lap with the result that the lens will engage the outer portions of the lap with the same pressure as it engages the central lower portion thereof.

Furthermore, as the spindle begins its return movement, the engagement of the contact arm with the roller 196 will immediately cause the spindle to be rotated in a counter-clockwise direction which, in turn, overcomes the inertia of the lens and tends to rock the lens holder 117 in the same direction and thereby swing the lens toward the center of the lap, that is, in the direction of axial travel of spindle 46. In other words, the swinging of the lens holder 117 produced by the frictional engagement of a contact arm 195 with the roller 196 produces a corresponding swinging movement of the lens across the face of the lap and thereby overcomes the side thrust which would be otherwise produced between the lens and the lap.

It will be now observed that if a concave lens is mounted upon the lens holder as shown in Figure 15, the side thrust of the lens upon the lap would be the reverse of that when grinding a convex lens, that is, the side thrust of the lens would be against the center of the lap and, therefore, it is necessary to effect rotation of the spindle 46 and lens holder 117 in the opposite direction to overcome the side thrust when grinding a concave lens from that when grinding a convex lens. The adjustment of the compensating device to effect proper rotation of the spindle 46 when grinding convex lenses is readily accomplished by moving the contact plates 195 upwardly to bring the lower contact plate into frictional engagement with the roller 196 through the medium of the lever 207 and screw 206. As hereinbefore stated, the compensating device is used only when grinding surfaces having a complex curvature, and when grinding substantially flat surfaces or surfaces having only a slight curvature the function of the compensator is not required and the plates are readily moved to a neutral position out of engagement with the roller 196 by swinging the arm 207 to an intermediate position.

Lap adjusting means

In the process of grinding and polishing lenses, it often happens, as is well known, that the lens is inaccurately mounted upon the lens block so when the lens block is mounted in the lens holder the longitudinal and transverse axes of the lens do not accurately align with the corresponding axes of the grinding lap. Therefore, in order to readily bring the axes of the lens and of the grinding lap into registration with each other, I have provided a simple mechanism associated with the lap spindle 129 for adjusting the lap about its axis relative to the lens holder 117.

This mechanism, see Figures 1 and 2, comprises an arm 210 which is secured at one end to the

lower end of the spindle 129 to extend radially therefrom. The arm 210 has the outer end thereof extended through an elongated vertically disposed slot 211 formed in the lower portion of the extension 3 of the housing 1. The length of the slot 211 is sufficient to permit the vertical movement of the arm 210 therein during the movement of the spindle 129 from the operative to the inoperative positions thereof. The width of the slot 211 is sufficient to permit a limited swinging movement of the arm about the axis of the spindle 129 whereby the lap 128 carried by said spindle may be rotated to bring the longitudinal and transverse axes thereof in alignment with the corresponding axes of the lens carried by the lens holder 117. A control plate 212 for the arm 210 is secured to the housing 1 adjacent the slot 211. This control plate 212 is an L-shaped member having one leg thereof positioned in a horizontally disposed guide slot 213 formed in the outer face of the housing 1 to extend rearwardly from the slot 211. A screw member 214 is connected with this leg of the plate and extends through an elongated slot 213' formed in the housing at the base of the slot 213 into threaded engagement with a nut 214' positioned inside the housing for adjustably clamping the plate to the housing. The other leg of the plate is provided with an elongated vertically disposed slot 215 adapted to receive the outer end of the arm 210 therein. This slot 215 is of substantially the same length as the slot 211 but is of only about the same width as the adjacent end of the arm 210 so that as the plate is moved longitudinally of the housing 1 the arm 210 and spindle 129 will be rotated thereby, to bring the longitudinal and transverse axes of the lap into alignment with the corresponding axes of the lens.

Automatic time control

In order that the machine may be automatically stopped after a predetermined period of operation, I have provided a simple control mechanism for automatically bringing the drive shaft 21 out of operative connection with the source of power. This mechanism as illustrated in Figures 1, 3, 6 and 7, comprises a control lever 217 which, in this instance, is in the form of a rod having one end bent to form a U-shaped recess 217' for receiving the belt 193 therein as shown in Figure 1. The other end 217'' of the lever 217 is bent upwardly and extends through a U-shaped bracket 218 with the upper end thereof secured in any suitable manner as by a set screw 219 to a flanged or cup-shaped collar 220 which rests upon the upper end of bracket 218. The bracket 218 is secured to the lower portion of the housing 1 intermediate the ends thereof and rotatably supports end 217'' of lever 217. The lever 217 is yieldingly urged in a direction to move the belt 193 from engagement with the drive pulley 28 onto the idle pulley 29 by a spring 222 coiled upon the end portion 217'' of the lever with one end thereof engaging the bracket 218 and the other end connected with the lever as shown in Figures 1 and 7. The lever 217 is releasably maintained in position for holding the belt upon the drive pulley 28 against the action of spring 222 by a control arm 223 which extends vertically from the collar 220 upwardly. The control arm 223 is pivotally connected with the housing 1 as at 224 a short distance below the upper end thereof. The lower end of the arm is normally positioned within a recess 225 formed in the marginal flange 226 of the collar 220 when the lever 217 is in position for main-

taining the belt in engagement with the drive pulley 28.

A pair of guide pins 226 secured to the housing 4, one adjacent either side of the arm 223 near 5 the lower end thereof, co-acts with the pivot 224 for maintaining the arm against being displaced laterally by the action of the spring 222 upon the collar 220.

The lower end of the arm 223 is yieldingly 10 urged outwardly for engaging the recess 225 by a coil spring 227 positioned intermediate the arm a short distance below the pivot 224 and the housing 4. The upper end of the arm 223 is maintained against being moved inwardly by the 15 action of spring 227 by a push rod 228 loosely mounted for longitudinal sliding movement in a pair of studs 229 secured to the cover 2 as shown in Figures 1 and 3, and a collar 230 secured to said rod and which contacts with one of the 20 studs 229. The inner end of the push rod 228 extends a short distance over the upper marginal edge of an index disk 231 secured, as shown in Figure 3, to the upper end of shaft 232 which extends downwardly through the cover 2 and is 25 journaled in a bearing sleeve 233 secured to the under side of the cover 2 adjacent one side of the cam shaft 166 as shown in Figure 5. The lower end of the shaft 232 is operatively connected with the cam shaft 166 by a gear 234 and worm 235 30 secured respectively to said shafts.

It will be seen, therefore, that the disk 231 is rotated by the shaft 166 and said disk is provided with a plurality of, in this instance thirty, apertures 231' arranged in uniform circumferential spaced relation to each other and in concentric relation with the disk for alignment with the inner end of the push rod 228. These apertures 231' may be spaced apart a distance corresponding to the amount of travel of the disk during 40 one minute of operation of the machine, or any multiple or fraction of a minute as desired. A throw-out or control member 236 adapted to be received in the apertures 231' is associated with said disk for actuating the rod 228. This throw-out or control member 236, in this instance, is a 45 U-shaped member having one leg 237 thereof of considerably greater length than the other leg 237' and slidably mounted in a bore 232' provided in the upper end of shaft 232. The leg 237' of the member 236 is spaced from the other leg 237 a distance corresponding to the distance the apertures 231' are spaced from the axis of the shaft 232 and is adapted to be received in any one of the apertures 231'. It will now be observed that 50 the control member 236 may be brought into engagement with any one of the apertures 231' by lifting the same upwardly a short distance as illustrated by broken lines in Figure 3 and then revolving the member about the leg 237 as a pivot to bring the leg 237' into alignment with the desired one of said apertures. The inner end of push rod 228 is oppositely tapered to form cam surfaces 228'. These cam surfaces are normally maintained in the path of movement of the leg 237' of the control member 236 by the stop collar 230 and by the spring 227 acting through the medium of the arm 222.

It will now be observed that when the time control is in operation, the machine may be automatically stopped by the engagement of the throw-out member 236 with the push rod 228 at any multiple of one minute period of operation throughout thirty minutes by inserting the end 237' in one of the apertures '30' positioned rearwardly in the direction of travel of the disk from

the rod 228 corresponding to the number of minutes it is desired that the machine be maintained in operation. At the end of the selected time period the engagement of the end 237' with the inner end of the push rod 228 will effect sufficient outward longitudinal movement of said rod to bring the lower end of the control arm 223 out of registration with the slot 225 thereby releasing the collar 220 and permitting the spring 222 to rock the lever 217 outwardly sufficiently 10 to bring the belt from engagement with the drive pulleys 28 into operative engagement with the idle pulley 29. The outward swinging movement of the lever 217 is limited by a stop screw 240 screw threaded in the housing 4 and adapted to 15 engage a boss 241 provided on the collar 220 as shown in Figure 7.

In order that the belt 193 may be manually moved from the idle pulley 29 into operative engagement with the drive pulley 28, I have provided a control lever 242 which has one end thereof secured in the boss 241 and which extends forwardly from the collar 220 to a convenient position adjacent the forward end of the housing 1 as shown in Figure 1.

Although I have shown and particularly described the preferred embodiment of my invention, I do not wish to be limited to the exact construction shown as various changes both in the form and relation of the parts thereof may readily be made without departing from the spirit of the invention as set forth in the appended claims.

I claim:

1. In a surface grinding machine of the class having a grinding lap and a work holder mounted in co-operative relation therewith, in combination, operating means producing relative movement of the grinding lap and work holder to move the work carried by the work holder with compounded reciprocal and circular motions 35 in continuously changing paths across the face of the lap, said operating means including a clutch element, and means for actuating said clutch element to automatically reverse the direction of the circular motion at frequent intervals.

2. In a surface grinding machine of the class having a grinding lap and a work holder mounted in co-operative relation therewith, in combination, operating mechanism connected with one of said members for producing compounded reciprocal and circular motions thereof relative to the other member whereby the work carried by the work holder will be moved across the face of the lap in continuously changing paths, 50 said operating means including two drive members associated with the circular motion, a clutch element mounted between said drive members, and means actuated by the operating mechanism for producing relative movement of the clutch element and said drive members to connect the clutch element alternately with the drive members whereby the direction of the circular motion is reverse at frequent intervals.

3. In a surface grinding machine, a grinding element, a work holder element mounted in co-operative relation therewith, operating means for producing movement of a piece of work carried by the work holder element across the face of the grinding element in continuous changing paths 55 including a plurality of carrier members having movement relative to each other and connected with at least one of said elements, means rotatably supporting one of the carrier members, operating means for rotating said latter carrier 70

75

- member, and control means associated with said latter operating means for automatically reversing the direction of rotation of the rotatable carrier element at predetermined intervals.
5. In a surface grinding machine having a grinding element and a work holder element mounted in cooperative relation therewith, in combination, a case for supporting said elements, power operating means mounted in said case and connected with at least one of said elements to move the work carried by the work holder element across the face of the grinding element in continuous changing paths, and control means associated with the power operating means including a shaft rotatably mounted in said case and operatively connected with the operating means to be rotated thereby, an index disc operatively connected with said shaft and positioned exteriorly of the case, said disc having a plurality of apertures arranged in predetermined spaced relation with each other, a manually operable control member movable into engagement with any selected one of said apertures to be moved in unison with the disc, and a power switching means connected with said case and arranged in cooperative predetermined relation with the disc to be actuated by said control member for automatically discontinuing the operation of the machine after a predetermined period of operation thereof.
30. In a surface grinding machine, a grinding element, a work holder mounted in cooperative relation therewith, means including a control lever for producing relative movement of the grinding element and work holder toward each other to bring the work carried by said holder into engagement with the grinding element, pressure means set into operation by continued movement of said lever after the work and grinding element are in engagement with each other for producing pressure between said work and element, and pressure indicating means operatively connected with said lever and said pressure means, said pressure indicating means being of such a character that the same is rendered active by the cooperation of the lever and said pressure means only after the work contacts with the grinding element for indicating the pressure engagement of the work with said element.
45. In a surface grinding machine having a grinding element and a work holder mounted in cooperative relation therewith, in combination, means including a control lever for producing relative movement of the grinding element and the work holder toward each other to bring the work carried by said holder into engagement with the element, means including a spring set into operation by movement of said lever only after the work and element are in engagement with each other for producing a predetermined pressure between the work and element, and means including a dial and a pointer coacting with the lever and spring for indicating the amount of said pressure.
50. In a surface grinding machine having a grinding element and a work holder element mounted in cooperative relation therewith, in combination, means including a control lever for producing relative movement of the grinding element and work holder element toward each other to bring the work carried by said holder into engagement with the grinding element, means including a spring set into operation by movement of said lever only after the work and element are in engagement with each other for producing a predetermined pressure between the work and element, and pressure indicating means including a dial member resiliently connected with the lever by said spring so as to move with said lever prior to the engagement of the work with the grinding element, and a pointer actuated by said lever with respect to said dial subsequent to the contact of the work with the grinding element for indicating the amount of said pressure.
55. In a surface grinding machine, a grinding element, a work holder mounted in cooperative relation therewith, means including a control-lever for producing relative movement of the grinding element and work holder toward each other to bring the work carried by said holder into engagement with the element, means including a rock member set into operation by said lever only after the work and grinding element are in engagement with each other for producing a predetermined pressure between said work and element, and means co-acting with said rock member for intermittently decreasing the pressure between the work and grinding element during the operation of the machine.
60. In a surface grinding machine, a grinding element, a work holder mounted in cooperative relation therewith, means including a manually operated control member for producing relative movement of the grinding element and work holder toward each other to bring the work carried by said holder into engagement with said element, means including a cam member brought into operation by continued movement of the control member after the work and grinding element are in engagement with each other for producing a predetermined pressure between said work and element, and means for operating said cam to intermittently change the degree of pressure between said work and element during the operation of the machine.
65. In a surface grinding and polishing machine having a grinding element provided with a curved grinding surface, a work holding means including a spindle mounted to rock about an axis extending transversely of said grinding surface in a plane at one side thereof, operating means associated with said work holding means for producing reciprocative movement of the spindle to move the work carried by the work holding means back and forth across said grinding surface in pressure engagement therewith, and a compensating means including a relatively fixed element having operative engagement with the spindle and rendered effective by said reciprocative movement of the spindle for rocking said spindle and the work holding means in a direction to move the work carried thereby about said axis in the direction of movement of said work produced by the reciprocative movement with respect to the grinding surface.
70. In a surface grinding and polishing machine having a grinding element provided with a curved grinding surface, a work holding means including a spindle mounted to rock about an axis extending transversely of said grinding surface in a plane at one side thereof, operating means associated with said work holding means for producing reciprocative movement of the spindle to move the work carried by the work holding means back and forth across said grinding surface in pressure engagement therewith, and compensating means including a contact arm mounted in substantially a fixed position adjacent said spindle and frictionally associated with said spindle adapted to cooperate with the reciprocative movement for

producing a rocking movement of said spindle and the work holding means in a direction to move the work connected therewith about said axis in the direction of movement of said work produced by the reciprocal movement with respect to the grinding surface.

12. In a surface grinding and polishing machine having a grinding element provided with a curved grinding surface, a work holding means including a spindle mounted to rock about an axis extending transversely of said grinding surface in a plane at one side thereof, operating means associated with said work holding means for producing reciprocal movement of the spindle to move the work carried by the work holding means back and forth across said grinding surface in pressure engagement therewith, and compensating means including two resilient arms arranged one at either side of said spindle adapted to be frictionally associated with said spindle during the reciprocal movement thereof for producing rocking movement of the spindle in directions to move the work about said axis in the direction of movement of the work produced by the reciprocal movement with respect to the grinding surface, and manually operated means for selectively moving the arms into and out of cooperative relation with the spindle depending upon whether the grinding surface is of concave or convex curvature.

13. In a machine for grinding lenses wherein a grinding element provided with a curved grinding surface and a work-holder element are mounted in co-operative relation with each other with a lens carried by the holder element maintained in pressure engagement with the grinding element, in combination, operating means for producing relative reciprocating movement of the elements including a supporting member rotatably mounted to rock about an axis disposed transversely across said surface of the grinding element, means connecting one of the elements with said supporting member including a second supporting member arranged at one side of the axis of the first supporting member, and means pivotally connecting said second member to the first member whereby said one of the elements will be mechanically rocked forwardly by the frictional resistance produced between the lens and grinding element during said reciprocal movement about said axis in the direction of the reciprocating movement, said later means including relative adjusted members whereby the surface of the element carried thereby may be moved from a position at one side of the axis of rotation of the first member to a position at the opposite side of said axis so that a convex or concave lens may be ground in the manner set forth.

14. In a machine for grinding lenses, in combination, a grinding lap having a base axis and a cylinder axis arranged substantially normal to each other, a supporting member mounted to rotate about an axis extended substantially normal to one of said axes of the lap, operating means for reciprocating the supporting member longitudinally and laterally of said axis of rotation, a work-holder pivotally connected with the supporting member to rotate about an axis extending substantially parallel with said one of the axes of the grinding lap, said work-holder having a portion thereof positioned in a plane over the grinding lap in spaced relation to said axis of rotation of the supporting member, means releasably connecting the work to said portion of the work-holder positioned over the lap, and a com-

pensating means operatively connected with the supporting member and rendered effective by one of said reciprocal movements of the supporting members for alternating effecting rotation of said member in reverse direction.

15. In a machine for grinding lenses, in combination, a lap having a curved grinding surface provided with a base axis and a cylinder axis disposed in right-angular relation to each other, a supporting member mounted to rotate about an axis arranged substantially normal to one of said axes of said grinding surface, operating means for reciprocating the supporting member longitudinally and laterally of said axis of rotation, a work-holder pivotally connected with the supporting member to rock about an axis substantially parallel with the second one of said axes of the grinding surface, said work-holder having a work-holding element positioned in a plane over the grinding lap in spaced relation to said axis of rotation of the supporting member, and means releasably securing the work to said portion of the work-holder, said work-holder including members adjustable relative to each other whereby the work may be moved from a position with the surface thereof to be ground located intermediate the axis of rotation of the supporting member and said work-holding element to a position with said surface of the work located opposite the axis of rotation of the supporting member from the work-holding element for the purpose set forth.

16. In a machine for grinding lenses, in combination, a grinding lap having a base axis and a cylinder axis disposed in right-angular relation to each other, a supporting member mounted to rotate about an axis extending substantially normal of one of said axes of the lap, operating means for reciprocating the supporting member longitudinally and laterally of said axis of rotation, a work-holder comprising an inverted substantially U-shaped frame, means connected with the supporting member at opposite sides of said axis of rotation thereof and pivotally engaging the side members of the work-holder frame for rotatably supporting the frame with the transverse portion thereof located in a plane over the grinding lap and in outwardly spaced relation to said axis of rotation, and means securing the work to said transverse portion of the frame, said work-holder frame being provided with means for adjustably securing the transverse portion thereof to the side portions whereby the work-holder may be moved from a position with the surface of the work to be ground located at one side of the axis of rotation of the supporting member to the opposite side thereof for the purpose set forth.

17. In a surface grinding machine, a grinding lap, a work-holder mounted in co-operative relation therewith, means including a manually operated control element for producing relative movement of the grinding lap and work-holder toward each other to bring the work carried by said holder into engagement with the lap, said means also including a spring set into operation by movement of said control element only after the work and lap are in engagement with each other for producing a predetermined pressure between the work and lap, and a dial member mounted in co-operative relation with the control element, and connected with said spring so that the dial member will move in unison with the control element prior to the engagement of the work with the grinding lap and will remain stationary during continued movement of the control element following said engagement of the

work and lap, whereby the amount of pressure between the work and the lap may be readily determined by the co-action of said element and dial.

- 5 18. In a surface grinding machine, a grinding lap, a work-holder mounted in co-operative relation therewith, means for moving the lap toward and from the work-holder to bring the work carried by said holder into pressure engagement with said lap, said means including an oscillating arm operatively connected with the lap, a manu-

ally operated lever, means including a spring yieldingly connecting the lever with said arm, and a dial member connected with the arm to move therewith and arranged in co-operative relation with the lever for indicating the amount of pressure between the work and the grinding lap. 5

19. A grinding machine as in claim 18 having means connected with said lever for intermittently changing the degree of pressure between the work and the lap.

WILLIAM A. LOCKHART. 10
